UNITED STATES PATENT OFFICE.

STEPHEN C. MASON, OF PITTSBURG, PENNSYLVANIA, ASSIGNOR TO McCONWAY AND TORLEY COMPANY, OF PITTSBURG, PENNSYLVANIA, A CORPORATION OF PENNSYLVANIA.

CAR-COUPLING.

SPECIFICATION forming part of Letters Patent No. 738,727, dated September 8, 1903.

Application filed January 5, 1903. Serial No. 137,820. (No model.)

To all whom it may concern:

Be it known that I, STEPHEN C. MASON, a citizen of the United States, residing at Pittsburgh, in the county of Allegheny and State of Pennsylvania, have invented or discovered certain new and useful Improvements in Car-Couplers, of which improvements the following is a specification.

The invention described herein relates to certain improvements in car-couplers of the Master Car-Builders' or swinging-hook type, and has for its object certain improvements in the construction and arrangement of lock-sets and knuckle-opening devices.

The invention is hereinafter more fully described and claimed.

In the accompanying drawings, forming a part of this specification, Figure 1 is a sectional plan view of a Master Car-Builders' type of coupler having my improvements applied thereto, the plane of section corresponding to the upper surface of the swinging hook. Fig. 2 is a sectional elevation on plane indicated by the line II II, Fig. 1, showing the parts in normal or closed position. Fig. 3 is a similar view showing a locking block or pin in unlocking position and supported by the lock-set. Fig. 4 is a view similar to Figs. 2 and 3, showing a locking block or pin raised to effect a shifting of the knuckle. Fig. 5 is a perspective view of a locking-block, knuckle-opener, and lock-set; and Fig. 6 is a similar view of the same parts, illustrating a modification of my improvement.

In the practice of my invention the coupler as regards its head 1, knuckle 2, and locking-block 3 is constructed in the usual or any suitable manner, excepting in so far as regards certain changes in the locking-block hereinafter stated.

Suitable bearings on the end wall of the coupler are provided for the shaft 4, said shaft being provided with an arm 5, projecting radially therefrom in such manner that when the latter is rotated the arm will bear against the rear side of the tail of the knuckle and force the same to open position. A lever 6 is arranged within a vertical recess in the locking-block 3 and has its lower end con-

nected to the shaft 4 in any suitable manner, 50 as by a bent finger 7. The lever is provided with a lateral projection or finger 8, extending through opening in the side of the locking-block near its upper end in such manner that when the latter is raised as hereinafter 55 described the lever will be caused to move with the locking-block, and thereby rotate the shaft 4 to effect an opening of the knuckle. The opening in the side of the locking-block through which the finger 8 projects is made 60 of such a length as will permit of an upward movement of the locking-block to unlocking position before the shoulder 9 or lower end of the opening engages the finger 8, so that there will be no upward movement of the lever until the knuckle has been unlocked. The vertical slot or recess formed in the locking-block for the reception of the lever and the opening through which the finger 8 projects are so constructed and proportioned 70 that the lever may have a lateral movement therein, the lateral movement being such that when the locking-block is raised to unlocking position a shoulder 10 on the lever will move in under a shoulder on the locking-block, the 75 lower end of the locking-block conveniently forming such shoulder, and thereby lock or support the locking-block in its raised or unlocking position. The lever is so arranged and supported that the lateral movement is automatic. In the construction shown in Figs. 1 to 5, inclusive, the pivotal support for the lever is formed by a projection or lug 12 on the lever, having as its support the bottom wall of the coupler-head. In the construction shown 80 in Fig. 6 the pivotal support for the lever is formed by the finger 7 on the shaft 4, said finger being closed around the lower end of the lever sufficiently far to prevent accidental disengagement of the parts and the lug 12 being 85 omitted. It will be observed that the lever or lock set has its pivotal support so arranged that the lever is inclined or has a bias to move to operative or supporting position. In order to permit of a shifting of the lock-set by hand, 90 the finger 8 is made of sufficient length to extend through a horizontal slot 13, formed in the guide-box 14 for the locking-block. 95

In describing the operation of my improvement it will be supposed that the knuckle is closed and locked, the parts being in the position shown in Figs. 1 and 2. To unlock the 5 knuckle, the locking-block is raised to the position shown in Fig. 3, in which position the lever will move laterally on its pivotal support to bring the shoulder 10 under the locking-block and support the same in its 10 raised position. During this initial movement of the locking-block no vertical movement is imparted to the lever. While the parts are in this position the knuckle can be opened, and in its opening movement the projection 15 on the tail of the knuckle will strike against the shoulder 10 or other part of the lever 6 and shift the same laterally, thereby moving the shoulder 10 from engagement with the locking-block and permitting 15 the latter to drop onto the tail of the knuckle, so that the locking-block will be free to drop to locking position so soon as the knuckle is shifted to closed position, the tail of the latter passing from under the locking-block. 20 25 When it is desired to effect an opening of the knuckle simultaneous with the unlocking of the same, the locking block or pin is raised beyond unlocking position and during this further movement will draw up the lever with 30 it, thereby rotating the shaft 4 and opening the knuckle. The opening of the knuckle will effect a shifting of the lever to unlocking position by the striking of the inclined shoulder 15 against the projection 10, the same as 35 if the opening of the knuckle had been effected by hand. When the locking-pin is released after opening the knuckle, it will drop, and during the corresponding downward movement of the lever the inclined 40 lower edge of the projection 10 will strike against an inclined portion 15 on the tail of the knuckle, and thereby shift the lever to unlocking position and permitting the locking-block to drop onto the tail of the knuckle. 45 It will be observed that the locking block and lever will effect during their downward movement a back rotation of the shaft and knuckle, opening arm 5.

I claim herein as my invention—

- 50 1. A car-coupler of the Master Car-Builders' type having in combination a swinging hook or knuckle, a locking block or pin and a lock-set arranged within the locking-block and so pivotally supported at its lower end as to have a bias to a position to support the locking-block when the latter is raised to unlocked position, substantially as set forth.
- 55 2. A car-coupler of the Master Car-Builders' type having in combination a swinging

hook or knuckle, a locking block or pin, a lever arranged vertically within the locking-block, and having a pivotal support at one side near its lower end so as to have an inclination to move to a position to move when the latter is raised to locked position, and 65 normally held in inoperative position by the internal wall of the locking-block, substantially as set forth.

3. A car-coupler of the Master Car-Builders' type having in combination a swinging 70 hook or knuckle, a slotted locking-block, a lever loosely arranged in said block, said parts being so connected as to permit the block to move to unlocking position independent of the lever, and a shoulder on the 75 lever adapted to support the locking-block when raised, substantially as set forth.

4. A car-coupler of the Master Car-Builders' type having in combination a swinging 80 hook or knuckle, a slotted locking-block, a lever loosely arranged in the locking-block and provided with a finger projecting through an opening in the side of the locking-block, and having a shoulder adapted to support the locking-block when raised, substantially as 85 set forth.

5. A car-coupler of the Master Car-Builders' type having in combination a swinging hook or knuckle, a slotted locking-block, a lever loosely arranged in said slot and provided with a finger projecting through an 90 elongated opening in the said side of the locking-block and having a shoulder adapted to support the locking-block when raised, and a knuckle-opener connected to said lever, substantially as set forth.

6. A car-coupler of the Master Car-Builders' type having in combination a swinging hook or knuckle, a locking block or pin, a knuckle-opener, means operating automatically to support the locking block or pin in unlocking position and forming an operative connection between the locking-block and the knuckle-opener, substantially as set forth.

7. A car-coupler of the Master Car-Builders' type having in combination a swinging hook or knuckle, a locking pin or block, a lever movable by the locking-block and adapted to support the locking-block when raised, and a knuckle-opener connected to said lever, 105 substantially as set forth.

In testimony whereof I have hereunto set my hand.

STEPHEN C. MASON.
